Primary Examiner — Andrew T Nemeth*Assistant Examiner* — Gary N Chamberlin(74) *Attorney, Agent, or Firm* — JCIPRNET(57) **CLAIM**

The ornamental design for a display screen or portion thereof with graphical user interface as shown and described.

DESCRIPTION

The FIGURE is a front view of a display screen or portion thereof with graphical user interface showing our new design.

The dot-dash broken line illustrates a display screen or portion thereof and forms no part of the claimed design. The even-dash broken lines illustrate portions of the graphical user interface that form no part of the claimed design.
